UNITED STATES PATENT OFFICE.

JOHN FRANK MACDONALD, OF CHESTER, PENNSYLVANIA.

GRINDING-TOOL.

1,392,426.

Specification of Letters Patent.

Patented Oct. 4, 1921.

Application filed October 12, 1920. Serial No. 416,479.

To all whom it may concern:

Be it known that I, JOHN FRANK MACDONALD, a citizen of the United States, residing at Chester, in the county of Delaware and State of Pennsylvania, have invented new and useful Improvements in Grinding-Tools, of which the following is a specification.

This invention relates to grinding tools 10 and has for its object the provision of a tool designed for grinding or boring out engine cylinders while the engine is still in position on the chasses, the idea being to true up the bore of the cylinder for fitting new or over-sized pistons therein.

An important object is the provision of a device of this character including a plurality of grinding shoes and provided with means whereby these shoes may be expanded 20 or moved outwardly to vary the diameter of the hole bored or ground out so that the device may be used in cylinders of different sizes.

An additional object is the provision of a 25 device of this character which will be comparatively simple and inexpensive, highly efficient in use, durable in service, and a general improvement in the art.

With the above and other objects and advantages in view, the invention consists in the details of construction to be hereinafter more fully described and claimed and illustrated in the accompanying drawings in which—

35 Figure 1 is a side elevation of my device showing the complete apparatus,

Fig. 2 is an enlarged side elevation of the grinder head alone,

Fig. 3 is a cross sectional view on the line 40 3—3 of Fig. 1,

Fig. 4 is a longitudinal sectional view through the grinder head,

Fig. 5 is a cross sectional view therethrough on the line 5—5 of Fig. 4,

45 Fig. 6 is a detail view of one of the adjusting washers, and

Fig. 7 is a detail end elevation of the body.

Referring more particularly to the drawings, the numeral 10 designates a supporting frame which is adapted to be engaged upon the engine, the cylinders of which are to be bored out and this frame includes an upright portion 11 provided at its lower end with 55 feet 12 and further includes a horizontal upper portion 13. Journaled through this

support is a vertical shaft 14 upon which is splined a bevel gear 15 meshing with a bevel gear 16 on a horizontal shaft 17 adapted to be rotated by any desired means. Surrounding the shaft 14 intermediate its ends is a bushing 18 which carries a yoke 19 having right angularly bent ends 20 revolvably engaged upon the shaft and held against longitudinal movement upon the shaft by a set 60 collar 21. This yoke is formed with rack teeth 22 engaged by a pinion 23 journaled on an extension 24 at the free end of the horizontal arm 13. The shaft 14 is rotated by rotating the shaft 17 and is fed downwardly 70 by turning the pinion 23 by means of a suitable handle 25. The above described mechanism is the machine with which is associated my novel grinding device.

My grinding device comprises a body 26 75 which is of the shape of a Maltese cross in cross section and includes a plurality of radial arms 27. This body is formed centrally with a hole 28 revolvably engaged upon the lower end of a shaft 29. Disposed 80 upon the shaft 29 above this body 26 is a circular disk 30 keyed upon the shaft and provided with a hole 31 within which is engaged a pin 32 carried by a collar 33 on the shaft 29. The upper end of this shaft 29 is threaded 85 for engagement within a threaded socket in the lower end of the shaft 14. Disposed upon the shaft 29 below the body 26 and keyed in place is a disk 34 exactly corresponding to the disk 30. These parts are 90 held in place by a nut 35 threaded onto the lower end of the shaft 29. The confronting faces of the disks 30 and 34 are formed with spiral grooves 36 for a purpose to be described. 95

Associated with each arm 27 of the body 26 is a segment shaped shoe 37 which has its curved side open for holding a grinding member 38 which likewise has an arcuate face projecting beyond the shoe and which 100 is held in place by suitable screws or the like 39. This grinding member might be formed of emery, carborundum, or other suitable abrasive of a nature which will cut or grind away steel or iron. Formed upon the upper 105 and lower ends of the segments 37 are ribs 40 engaged within the spiral grooves 36 on the disks so that when the disks are rotated the grooves therein engaging these ribs will cause the grinding members to be protracted 110 or retracted, as the case may be. The body 26 has its arms 27 formed at intervals with

sockets 41 within which are engaged coil springs 42 abutting against the inner faces of the segments for normally forcing them outwardly and preventing any looseness.

5 In the operation of the device it will be seen that the support 10 with the mechanism carried thereby is placed upon the engine with the shaft 14 arranged co-axially with the cylinder to be bored out or ground. The 10 grinding device formed by the members 26 to 41 inclusive, is then brought into play and the shaft 29 thereof is threadedly connected with the shaft 14. The body 26 is then rotated with respect to the disks 30 and 34 15 to expand or retract the grinding members so that the diameter of the tool will be of the desired size. The pinion 23 is then operated to move the shaft 14 downwardly to bring the grinding member into the cylinder 20 to be bored, after which the shaft 17 is rotated to rotate the grinder. The grinder will of course grind away the cylinder walls and dress them smooth and to the proper diameter. The grinding member is of course 25 fed downwardly as required by means of the pinion 23 until the whole cylinder has been treated as desired.

While I have shown and described the preferred embodiment of my invention, it is of 30 course to be understood that I reserve the right to make such changes in the form, construction, and arrangement of parts as

will not depart from the spirit of the invention or the scope of the subjoined claims.

Having thus described my invention, I 35 claim:

1. A boring tool comprising a shaft, a body revoluble upon said shaft and formed cruciform in cross section whereby to have a plurality of radial arms, segment-shaped 40 shoes engaged upon said arms and carrying grinding members, and means for moving said shoes inwardly or outwardly, said means comprising disks secured upon said shaft and having their confronting faces 45 formed with spiral grooves, and lugs projecting from the ends of the shoes and engaged within said spiral grooves.

2. A boring tool comprising a shaft, a body revoluble upon said shaft and cruci- 50 form in cross section whereby to have a plurality of radial arms, said arms being each formed with a plurality of sockets, segment shaped shoes slidably associated with said arms and having sockets within which said 55 springs have their outer ends engaged, grinding members carried by said shoes, ribs projecting outwardly from the ends of said shoes, and disks carried by said shaft and formed on their confronting faces with spi- 60 ral grooves engaging said ribs.

In testimony whereof I affix my signature.

JOHN FRANK MacDONALD.
